(57) **CLAIM**

The ornamental design for a two-piece contoured metallic container, as shown and described.

DESCRIPTION

FIG. 1 is a front perspective view of the two-piece contoured metallic container;

FIG. 2 is a front elevation view thereof;

FIG. 3 is a top plan view thereof; and,

FIG. 4 is a bottom plan view thereof.

The broken lines showing a two-piece contoured metallic container are included for the purpose of illustrating environment and form no part of the claimed design.
